UNITED STATES PATENT OFFICE.

ALFRED H. SANDER, OF MAPLEWOOD, NEW JERSEY, ASSIGNOR TO GEORGE BORGFELDT & CO., OF NEW YORK, N. Y., A CORPORATION OF NEW JERSEY.

DESIGN FOR A DOUBLE BOILER OR SIMILAR ARTICLE.

Application filed September 10, 1921. Serial No. 499,833. Term of patent 3½ years.

To all whom it may concern:

Be it known that I, ALFRED H. SANDER, a citizen of the United States, residing at No. 92 Roland Avenue, in the village of Maplewood, county of Union, and State of New Jersey, have invented a new, original, and ornamental Design for a Double Boiler or Similar Article, of which the following is a specification, reference being had to the accompanying drawing, forming a part thereof.

Fig. 1 shows a side view of a double boiler embodying my design.

Fig. 2 is a cross-sectional view along the line 2—2 of Fig. 1, showing the shape of the handles.

It is to be understood that my claim includes all substantial equivalents of my design as shown and described.

I claim:

The ornamental design for a double boiler or similar article, substantially as shown and described.

ALFRED H. SANDER.
